CROSSBELT MAGNETIC SEPARATOR

Karl A. Blind, Thiensville, Wis., assignor to Dings
Magnetic Separator Co., Milwaukee, Wis., a
corporation of Wisconsin

Application December 3, 1947, Serial No. 789,497

3 Claims. (Cl. 209—223)

1

My present invention relates in general to improvements in the magnetic separation art, and relates more specifically to various improvements in the construction and operation of equipment for effecting separation of magnetic particles from a mixture of magnetic and non-magnetic granular materials while such mixture is advancing through one or more fields of magnetic influence.

The principal object of the present invention is to provide improvements in magnetic separators of the general type forming the subject of my copending application Serial No. 747,229, filed May 10, 1947, whereby the efficiency and capacity of such separators may be augmented.

In my prior application above identified, I have shown and described an improved cross-belt type of magnetic separator having a main conveyor for transporting mixed magnetic and non-magnetic granular material along a definite path, a transversely movable auxiliary conveyor disposed somewhat above and spanning the said path, a pair of lower and upper complementary zone poles disposed beneath and above the main and auxiliary conveyors respectively, and means for energizing the zone poles so as to create a field of magnetic influence at the gap between the conveyors sufficiently intense to separate magnetic particles from the bulk mixture and to suspend these particles from the advancing auxiliary conveyor. This prior cross-belt separator embodies a lower zone pole having a smooth flat face coating with the underside of a main mixed material conveying belt, and a complementary zone pole coating with top surface of an auxiliary magnetic particle removing cross-belt, the latter zone pole having a series of parallel wedge faces or ridges the edges of which are spaced equidistant from the flat face of the lower pole and extend in the direction of travel of the auxiliary belt. In accordance with my prior disclosure, two sets of these specially constructed complementary zone poles were energized by means of a common pair of coils and were associated with successive advancing portions of the main conveyor belt, thus providing two spaced separating zones or magnetic fields of equal intensity each having a pair of coating relatively fixed zone poles composed of material having uniform permeability throughout.

I have now discovered that the efficiency of such serrated or ridged zone poles may be materially enhanced by providing ridge tips or edges composed of material having higher permeability than that utilized in the remaining major por-

2

tions of the poles, thereby causing more of the flux tubes to pass through the air gap remote from the ridge apices and providing more uniform distribution of these tubes throughout the magnetic zone thus also augmenting the lifting force. I have also found that in order to increase the utility and effectiveness of such cross-belt separators and to adapt them for the treatment of materials having variable magnetic characteristics,

10 it is desirable to vary the width of the air gap between the complementary zone poles; and I have moreover discovered that more efficient removal of the magnetic particles may also be accomplished by providing a succession of magnetic separating units disposed along the path of advancement of the mixed material and each having a set of coating zone poles provided with independent magnetizing coils, the auxiliary belts of the successive units being movable in opposite 15 directions while the belts of alternate units move in the same direction transversely of the main conveyor path. These several features applied to a cross-belt magnetic separator, have been found to materially increase the efficiency, to enhance 20 its flexibility and adaptability, and to augment its capacity.

It is therefore a more specific object of the present invention to provide an improved zone pole construction for magnetic separators, and which is especially adapted for advantageous 30 embodiment in the cross-belt type of separator.

Another specific object of the invention is to provide an improved zone pole assemblage for magnetic separators wherein the air gap between complementary sets of poles may be readily enlarged or diminished.

35 A further specific object of my invention is to provide an improved unit for cross-belt magnetic separators or the like, wherein a set of complementary zone poles is energized and caused to cooperate with main and auxiliary material conveyors so as to most effectively separate magnetic from non-magnetic particles being constantly advanced by the conveyors.

40 Still another specific object of the invention is to provide an improved cross-belt magnetic separator assemblage embodying a main conveyor belt having a succession of independent local interchangeably similar separating units 45 disposed at spaced intervals therealong and adapted to deliver removed magnetic particles in opposite directions away from the path of advancement of the bulk material by the main conveyor.

50 An additional specific object of the present

invention is to provide various improvements in the construction and operation of cross-belt magnetic separators whereby highly efficient automatic functioning results and which may be conveniently adjusted to meet varying conditions of use.

These and other specific objects and advantages of the invention will be apparent from the following detailed description.

A clear conception of the improved features and of the mode of constructing and operating a typical multi-unit cross-belt magnetic separator embodying the invention, may be had by referring to the drawings accompanying and forming a part of this specification wherein like reference characters designate the same or similar parts in the various views.

Fig. 1 is a side elevation of a typical multi-unit cross-belt magnetic separator assemblage embodying features of the present invention;

Fig. 2 is a top view of the multi-unit magnetic separator of Fig. 1, showing the same in action;

Fig. 3 is a somewhat enlarged end view of the multi-unit cross-belt magnetic separator, looking toward the main endless conveyor drive;

Fig. 4 is a similarly enlarged transverse cross-section through the same magnetic separator, taken along the line 4—4 of Fig. 1 and looking in the direction of the arrows;

Fig. 5 is a likewise enlarged transverse cross-section through the same magnetic separator, taken along the line 5—5 of Fig. 1 and looking in the direction of the arrows;

Fig. 6 is a further enlarged transverse cross-section through the assemblage, similar to that of Fig. 5, but showing additional improved details of construction;

Fig. 7 is a likewise further enlarged side view of one of the improved magnetic separator units;

Fig. 8 is a still further enlarged fragmentary cross-section through a set of complementary asymmetrical zone poles, the section having been taken along the line 8—8 of Fig. 6;

Fig. 9 is a similar cross-section through a succeeding adjacent set of the same type of zone poles; and

Fig. 10 is an elevation of a complementary set of symmetrical zone poles embodying the invention.

While the invention has been shown and described herein as being especially advantageously applicable to a multi-unit cross-belt magnetic separator having a series of interchangeably similar reversely disposed magnet units cooperating with a common main conveyor belt, it is not my desire or intention to unnecessarily limit the scope or utility of the improved features by virtue of this restricted embodiment, since some of these features are obviously more generally applicable to other types of magnet assemblages.

Referring to the drawings, the typical multi-unit cross-belt magnetic separator shown therein, comprises in general an elongated rigid frame composed of a pair of laterally spaced parallel channel bars 11 interconnected by tie-bolts 12; a main endless belt conveyor 14 coating with pulleys 15, 16 journaled for rotation in bearings mounted upon the opposite ends of the frame bars 11, and having an upper stretch or run for constantly advancing a relatively thin layer 17 of granular material from one end of the frame toward the other; a material supply hopper 18 mounted upon the frame near the feed end of the conveyor 14; a variable speed propelling motor 19 for the conveyor 14 mounted upon the

opposite end of the frame and being drivingly connected to the pulley 16 through reduction gearing 20; a low intensity magnetic scalping unit 21 mounted upon the main frame and cooperating with the bulk material layer 17 near the feed hopper 18; and a succession of interchangeably similar but reversely disposed higher intensity cross-belt magnetic separating units 23, 24 cooperating with the advancing layer 17 at spaced intervals between the scalper 21 and the discharge end of the main conveyor 14.

The main frame may be of any suitable length depending upon the number of units 23, 24 included in the separator assembly, and in addition to the tie-bolts 12, the channel bars 11 of the main frame are firmly united by the bases of the hopper 18, the reduction gearing 20, the scalping unit 21, and the separating units 23, 24. The lower stretch or run of the main conveyor belt may be supported against excessive sagging by a succession of rollers 25 journaled in bearings mounted upon the channel bars 11 as shown in Fig. 5; and while the belt carrying pulley 16 is mounted in fixed bearings, the opposite end pulley 15 is journaled in movable bearings which may be adjusted with the aid of tensioning devices 26 so as to properly stretch the belt runs, see Figs. 1 and 2. The material supply hopper 18 located at the feed end of the upper run of the main conveyor 14, should be abundantly filled with bulk material consisting of a mixture of magnetic and non-magnetic particles, and this hopper 18 should also be adapted to deposit a relatively thin and uniform layer 17 of the mixed materials upon the constantly advancing upper run of the main conveyor 14.

The main conveyor propelling motor 19 is preferably of the variable speed type so that the conveyor 14 and the layer 17 of material resting thereon may be continuously advanced at any selected speed; and the initial or scalping unit 21 is preferably of relatively low intensity electromagnetic type adapted to promptly separate and remove a considerable portion of the highly magnetic particles embodied in the advancing layer 17. This initial unit 21 is shown generally in Figs. 1 and 2, and more in detail in Fig. 4, and consists primarily of a top pole assembly 28 and a lower belt support 27 separated by an air gap through which the layer 17 of mixed materials is advanced by the main conveyor 14 coating with the support 27; an endless auxiliary cross-belt 29 coating with pulleys 30, 31 and having a lower stretch movable transversely across the main conveyor 14 in a close proximity to the upper pole 28; a variable speed electric motor 33 drivingly associated with the pulley 30 at one end of the conveyor belt 29; a magnetic particle discharge chute 34 disposed beneath the lower run of the belt 29 and below the pulley 31 beyond the main conveyor 14; and electric coils 35 for energizing the magnets so as to produce a field of magnetic influence at the air gap, these coils 35 being located between the lower and upper stretches of the conveyor belt 29. The scalping unit 21 is of relatively well known construction and operation, and is preferably located near the supply hopper 18, as illustrated in Figs. 1 and 2.

The interchangeably similar but reversely disposed subsequent cross-belt magnetic separating units 23, 24 are however of improved construction and disposition, and each of these individual units comprises a lower pole support 36 mounted upon the main frame channel bars 11 and carry-

ing opposite upright side plates 37, 38 which contact with a top plate 39 to provide a magnetic loop; a lower zone pole 40 having a smooth top face coacting with the bottom surface of the upper run of the main conveyor 14, and also having an inclined lower face resting upon the upper surface of an adjusting wedge 41 which in turn rests upon the loop support 36; an upper zone pole 43 spaced vertically from the complementary zone pole 40 to provide an air gap and being detachably secured to and suspended from a magnetizing core 44 which is carried by the top plate 39 of the loop and is embraced by energizing windings or coils 45; an endless auxiliary cross-belt 46 coacting with upper and lower pulleys 47, 48 journaled for rotation in bearings carried by the loop frame, the belt 46 having a lower stretch movable across the main conveyor 14 in contact with the lower face of the upper zone pole 43; a variable speed electric motor 49 drivingly associated with one of the upper auxiliary belt supporting pulleys 47; and a magnetic particle discharge chute 50 suspended from the loop beneath the lower stretch of the belt 46 and below the motor 49 laterally beyond the main conveyor belt 14.

While all of these cross-belt units 23, 24 are of identical construction, the successive units are reversed relative to the main belt 14 which passes through the air gaps of all units, so that the lower runs of the successive cross-belts 46 travel in opposite directions and deliver separated magnetic particles 51 to successive discharge chutes 50 located on opposite sides of the main conveyor 14. Each of the cross-belt propelling motors 49 may be operated at any selected speed, and the vertical width of the air gap in each unit 23, 24 may be varied to suit the operating conditions at the successive separating zones, either by raising or lowering the lower zone pole 40 with the aid of the adjacent supporting wedge 41, or by replacing the removable upper zone pole 43 with another having greater or lesser height. The lower zone pole 40 of each complementary set is fixed against lateral displacement by means of several guide screws 53 with which compression springs 54 coact to constantly urge the pole 40 against the adjoining wedge 41, and each of these wedges 41 is adapted to be shifted laterally beneath the adjacent pole 40 to vary the air gap, with the aid of a threaded rod 55 coacting with screw threads in the wedge and journaled for rotation in the adjoining loop support 36, the rod 55 being rotatable by means of a hand wheel 56, see Fig. 6. The wedge 41 of each unit is also provided with slots 57 as shown in Figs. 6 and 9 for permitting adjustment without interference by the screws 53, and a suitable gage 58 for indicating the degree of adjustment may also be provided.

The upper zone pole 43 of each complementary pair is provided with a gap widening pole 59 projecting from its material delivery end, and is detachably secured to the lower end of the adjacent core 44, by means of screws 60 coacting with flange plates 61 secured to the pole 43. The widening poles 59 may be detachably attached to their supporting poles 43 by bolts 63 piercing the latter, and by replacing the upper zone poles 43 with others having different height, the vertical height of the adjacent air gaps may be readily varied. The face of each upper pole 43 which coacts with the adjacent cross-belt 46, is preferably of improved construction, and as shown in Figs. 8 and 9, the bottom face of each pole 43 is provided with a series of parallel asymmetrical

wedge shaped ridges 64 extending thereacross and each having a lower triangular edge portion 65 formed of magnet material having considerably higher magnetic permeability than the upper portion of the pole. These edge portions 65 may be secured to the upper portions of the poles in any suitable manner as by fusion of metals, and the gaps between the ridges are preferably spanned by angular sectional strips 66 of non-magnetic material welded or otherwise secured to the zone pole 43, so as to provide a smooth and approximately plane bearing surface for the belt 46, see Figs. 8 and 9.

In the asymmetrical wedge ribbed type of zone pole 43 shown in Figs. 8 and 9, the main conveyor belt 14 should always advance through the zone of magnetic influence in a direction approaching the inclined sides of the ridges 64 and away from the perpendicular bounding surfaces thereof, in order to obtain best and most efficient distribution of the flux tubes, but the lower face of the upper zone pole 43 may also be advantageously formed with symmetrical ridges 64' each having a lower triangular edge portion 65' of material having high magnetic permeability, as illustrated in Fig. 10. These modified ridges 64' provided with special lower tip portions 65', also span the zone pole 43 and will quite effectively distribute the flux tubes throughout the magnetic field or zone with the conveyor belt travelling therethrough in either direction, but they are not quite as effective theoretically as the asymmetrical ridges 64. As in the embodiment of Figs. 8 and 9, the gaps between the modified ridges 64' of Fig. 10, may also be spanned by non-magnetic strips 66 in order to provide a smooth bearing surface for the belt 46.

It has been found by actual test, that saturation or high concentration of magnetic flux occurs at and near the apices of the ridges of the pole pieces 43, and it is well known that if a magnetic circuit is saturated beyond approximately 22,000 gauss, additional magnetomotive force or ampere turns will increase the amount of field in the same proportion as the added magnetomotive force impressed upon the circuit. In other words, the advantage of ferric permeability is lost and the material near the tips of the pole ridges could be virtually replaced by air or a vacuum. Effective lifting force can be obtained only with maximum taper of the flux tubes extending from the upper pole tips or ridges to the lower pole. Any additional amount of flux will therefore pass through the air gap away from each apex, thus enlarging the pick-up zone but reducing the field intensity, so that the gradient of the field is materially reduced. The geometrical distribution of the field will then be equivalent to that of a field existing in the gap if the ridge tips were rounded off with a large radius, but this objection can be eliminated by forming the tip portions of the ridges of material having exceptionally higher magnetic permeability than low carbon steel, that is, material having higher saturation point, in accordance with my present invention. The use of these improved ridge tips improves the configuration of the field to the same extent as the increase in saturation point, and the result is increased attraction or lifting force.

When the improved cross-belt magnetic separator has been properly constructed and assembled as herein described, it may be placed in normal operation by merely supplying the hopper 18 with an abundance of mixed material, by energiz-

ing the magnet coils 35, 45, and by operating the electric motors 19, 33, 49 to cause the endless conveyor belts 14, 29, 49 to advance in the directions indicated by the several arrows associated with these belts in the various views. The continuously advancing relatively thin layer 17 of the mixture resting upon the upper stretch of the main conveyor 14 will be carried progressively past the scalper unit 21 and past the series of reversely disposed cross-belt units 23, 24, and the magnetic particles 51 of the mixture will be automatically separated and removed while the residual non-magnetic particles will ultimately be discharged from the end of the main conveyor 14 beneath its propelling motor 19. The scalping unit 21 removes a considerable portion of the highly magnetic particles 51 and the cross-belt 29 thereof removes these separated particles from the initial separating zone and delivers them by gravity into the discharge chute 34. The subsequent units 23, 24, gradually likewise separate and remove more and more of the magnetic particles 51, and the belts 46 of these units likewise deliver the particles 51 to the successive discharge chutes 50 located on opposite sides of the main conveyor belt 14, so that very little valuable material remains in the residue discharged at the delivery end of the main conveyor.

The speed of the main conveyor belt 14 may be varied to insure maximum capacity, and the speeds of the auxiliary cross-belts 29, 46 of the successive independent units 21, 23, 24 may also be varied independently of each other so as to insure maximum efficiency. Then too, the vertical widths of the gaps at the several separating zones may be quickly and conveniently varied or adjusted to meet different operating conditions, either by substituting upper zone poles 43 of different heights, or by merely moving the wedges 41 with the aid of the hand wheels 56, and the latter adjustment may be effected at any of the separating fields independently of all others. It is to be noted that when a wedge 41 is moved laterally, the corresponding lower zone pole 40 merely moves vertically and not laterally, thus maintaining its proper position relative to the path of advancement of the material layer 17.

From the foregoing detailed description it will be apparent that my invention provides various improvements in the construction of magnetic separators whereby the capacity and efficiency thereof may be materially enhanced, and which may be accurately adjusted and manipulated to most effectively treat materials having difference characteristics. The improved upper zone pole structure having ridge tips of high permeability, makes it possible to obtain maximum lifting effect throughout the entire separating zones, and the removability of these upper poles 43 combined with the vertical adjustability of the lower zone poles 40 also makes it possible to readily vary the magnitude of the gaps so as to insure most efficient separation of the magnetic particles 51 from mixed materials having a wide range of characteristics. The provision of interchangeably similar cross-belt units 23, 24 not only reduces the cost of construction of the entire separator assemblage to a minimum, but also enables the capacity of the separator to be enlarged or diminished by merely providing more or less of these units cooperating with a common main conveyor 14; and by making these units 23, 24 independently controllable it is possible to obtain most effective separation at each of the successive zones. The reversal of the suc-

cessive units 23, 24 moreover tends to agitate the particles of the advancing layer 17 so as to free the magnetic particles from the non-magnetic material, and by providing for variation in speed of travel of the belts 14, 29, 46 both the bulk material and the separated particles may be advanced at maximum speed commensurate with greatest capacity.

While the provision of ridge tips 65 having high magnetic permeability is an important feature of my invention, the relative adjustability of the zone poles 40, 43 so as to vary the intervening gap is also important. The wedge adjustment permits the lower pole 40 to be raised or lowered without shifting it laterally, since the screws 53 positively prevent such lateral shifting and the springs 54 always maintain effective contact between the wedge 41 and the adjacent surfaces of the pole 40 and support 36. The non-magnetic strips 63 provide smooth bearing surfaces for the cross-belts 46 without interfering with the effectiveness of the ridged or serrated pole faces, and the ridges 64, 64' may be formed either asymmetrical as in Figs. 8 and 9, or symmetrical as in Fig. 10 and any desired number of these ridges may be provided. The invention has proven highly successful and satisfactory in actual use, and while all features have been shown as being applicable to cross-belt separators some of these features are obviously more generally applicable to other types of magnetic separators.

It should be understood that it is not desired to limit this invention to the exact details of construction or to the precise mode of operation of the structures herein shown and described, for various modifications within the scope of the appended claims may occur to persons skilled in the art; and it is also contemplated that specific descriptive terms used herein be given the broadest possible interpretation consistent with the disclosure.

I claim:

1. In a magnetic separator, a continuous magnetic loop having opposite side members firmly interconnected by rigid top and bottom members, a magnetic core suspended from said top member and extending across the major portion of the interior of said loop but being spaced from said bottom member, an energizing coil surrounding said core within said loop, a main mixed material conveyor movable through the space between said core and said bottom member, an auxiliary magnetic material conveyor also movable through said space across and above said main conveyor and being separated from the latter by a magnetic field gap, an upper magnet pole interposed between said core and said auxiliary conveyor, a lower magnet pole interposed between said main conveyor and said bottom member and having a plane lower surface spaced from and inclined toward and along the upper plane surface of said bottom member, and a wedge of magnetic material coating with said plane relatively inclined surfaces and being adjustable longitudinally of said bottom member to vary the size of the gap between said conveyors.

2. In a magnetic separator, a continuous magnetic loop having opposite side members firmly interconnected by rigid top and bottom members, a magnetic core suspended from said top member and extending across the major portion of the interior of said loop but being spaced from said bottom member, an energizing coil surrounding said core within said loop, a main mixed mate-

rial conveyor movable through the space between said core and said bottom member, an auxiliary magnetic material conveyor also movable through said space across and above said main conveyor and being separated from the latter by a magnetic field gap, an upper magnet pole interposed between said core and said auxiliary conveyor, a lower magnet pole interposed between said main conveyor and said bottom member and having a plane lower surface spaced from and inclined toward and along the upper plane surface of said bottom member, a wedge of magnetic material coating with said plane lower pole and bottom member surfaces and extending entirely across the lower pole and longitudinally of the bottom member, and a jack screw coacting with a side of said loop and with said wedge for adjusting the latter along said bottom member to vary the size of said field gap.

3. In a magnetic separator, a continuous magnetic loop having opposite side members firmly interconnected by rigid top and bottom members, a magnetic core suspended from said top member and extending across the major portion of the interior of said loop but being spaced from said bottom member, an energizing coil surrounding said core within said loop, a main mixed material conveyor movable through the space between said core and said bottom member, an auxiliary magnet material conveyor also movable through said space across and above said main conveyor and being separated from the latter by a magnetic field gap, an upper magnet pole interposed between said core and said auxiliary conveyor, a

lower magnet pole interposed between said main conveyor and said bottom member and having a plane lower surface spaced from and inclined toward and along the upper plane surface of said bottom member, a wedge of magnetic material coating with said plane lower pole and bottom member surfaces and extending entirely across the lower pole and longitudinally of the bottom member, a jack screw coacting with a side of said loop and with said wedge for adjusting the latter along said bottom member to vary the size of said field gap, and resilient means for constantly urging said lower pole and said bottom member into intimate contact with said wedge.
